(57) **CLAIM**

The ornamental design for a driver bit, as shown and
described.

DESCRIPTION

FIG. 1 is an isometric view of a driver bit showing my new
design.

FIG. 2 is a front elevation view of the driver bit of FIG. 1,
the rear elevation view being identical.

FIG. 3 is a right side elevation view of the driver bit of FIG.
1, the left side elevation view being identical.

FIG. 4 is a top end view of the driver bit of FIG. 1; and,
FIG. 5 is a bottom end view of the driver bit of FIG. 1.

The portions of the drawings appearing in broken line are for
environment only and do not form a part of the design.

1 Claim, 3 Drawing Sheets
